5,317,822 A 6/1994 Johnson

FIG. 1 is a side perspective view of an outsole cover showing our new design;

FIG. 2 is a top plan view thereof;

FIG. 3 is a first side elevational view thereof;

FIG. 4 is an opposite side elevational view thereof;

FIG. 5 is front elevational view thereof;

FIG. 6 is back elevational view thereof; and,

FIG. 7 is a bottom plan view thereof.

The broken lines in the Figures represent boundaries of the design and portions of the outsole cover that form no part of the claimed design. The broken lines form no part of the claim.
